UNITED STATES PATENT OFFICE.

ALBERT P. M. KLOSTERMANN AND HUGO O. R. LUBKE, OF HOBOKEN, NEW JERSEY.

STOPPLE.

Application filed March 29, 1922. Serial No. 547,744.

To all whom it may concern:

Be it known that we, ALBERT P. M. KLOSTERMANN and HUGO O. R. LUBKE, citizens of Germany, residing at Hoboken, in the county of Hudson and State of New Jersey, have invented certain new and useful Improvements in a Stopple; and we do hereby declare the following to be a full, clear, and exact description of the invention, such as will enable others skilled in the art to which it appertains to make and use the same.

This invention relates to a stopple or closure for bottles and like receptacles.

An aim is to provide a stopple which may be used and reused and still maintained in a sanitary condition in that handling thereof is avoided.

A further important object is to provide such a stopple having a novel bail or lock manufacturable from a single strand of resilient metal, particularly wire, and adapted to cooperate with a shoulder on the bottle neck.

Additional objects and advantages will become apparent from a consideration of the description following taken in connection with accompanying drawings illustrating one practical embodiment.

In said drawings:

Figure 1 is a side elevation illustrating the stopple in place;

Figure 2 is a vertical sectional view illustrating the bail or lock in an open position;

Figure 3 is a detail perspective view of the bail or lock and

Figure 4 is a detail perspective view of the stopple.

Like reference characters designate like or similar parts in different views.

To facilitate an understanding of the invention, a bottle has been fragmentarily shown at 10 having its neck about the mouth enlarged as at 11 to provide a shoulder at 12. This bottle is to be taken as a conventional illustration, not only of a bottle but of a receptacle generally, for instance a jar. The stopple used is designated 13 and may be of any general shape, having for instance a depending or seating portion 14 adapted to enter the bottle neck. A suitable washer or gasket as at 15, which may be of rubber for instance, is interposed between the mouth of the bottle and the stopple 13. Said stopple 13 may be made of any appropriate material for instance wood, metal, glass, porcelain or

a composition. At diametrically opposite points, recesses 16 are provided in the sides or periphery of the stopple 13.

A suitable lock or fastener for the stopple 13 is provided as at 17, being best detailed in Figure 3. This bail, lock or fastener 17 may be made of any suitable material but is preferably constructed from resilient metallic wire and in a single strand. The central portion of the lock or fastener 17 is formed into a loop at 18 which leads to coils 19 from which the strand is returned as arms 20 and which strand is bent into resilient eyelets at 21 and extended upwardly to form mounting arms 22 which cross the arms 20 and the loop 18 at a right angle and extend above the latter. The arms 22 have inwardly extending pintles at 23 which are disposed within the recesses 16 loosely or pivotally. The lock or fastener 17 is maintained attached to the stopple 13 through the resiliency of the lock and its engagement with the stopple at the pintles 23.

After the stopple 13 has been applied to the bottle 10, the lock or fastener is in the position shown in Figure 2. From that position, it is urged downwardly and inwardly toward the bottle whereby the loop 18 will bear against and resiliently engage the shoulder 12, limiting movement of the lock to such a position where the arms 22 are truly vertical where a downward pressure on the stopple 13 will be applied effectively and evenly. The loop 18 thus serves to resiliently and urgently maintain the stopple 13 in engagement with its seat. In order to remove the stopple 13 it is merely necessary to displace the loop 18 by moving the same out of engagement with the shoulder 12 for instance through pushing movement applied at the coils 19.

As merely one practical embodiment of the invention has been illustrated and described, it is to be understood that changes in the details may be resorted to provided they fall within the spirit and scope thereof as defined by appended claims.

We claim as our invention:

1. A closure consisting of a stopple, a fastener pivotally connected therewith, and a resilient attaching arm for contact with an abutment on the article to be closed crossing the fastener intermediate the fulcrum thereof and opposite ends thereof.
2. A closure consisting of a stopple, a fas-

tener arm extending from the stopple, and a resilient attaching arm for the fastener for contact with an abutment on the article to be closed and yieldable in a direction substantially longitudinally of the fastener.

3. A closure consisting of a stopple, a fastener having an arm pivoted to said stopple, and the fastener having a resilient attaching portion for contact with an abutment on the article to be closed crossing said arm intermediate its ends.

4. A closure consisting of a stopple, a fastener therefor having an arm pivoted thereto, a second arm, said second arm extending from the first arm and at an angle thereto, and a loop extending from the second arm across the first arm intermediate the second arm and the fulcrum of the fastener for contact with an abutment on the article to be closed, and said loop being yieldable in a

direction substantially longitudinally of the first mentioned arm.

5. A closure consisting of a stopple, a fastener therefor, said fastener being constructed of a single strand of wire and having an attaching loop intermediate its ends, arms substantially parallel with said loop, coils at the junction of said arms and loop, attaching arms extending from said arms and at an angle thereto across the loop, and 30 pintles on the attaching arms above the loop and pivotally connected to the stopple.

In testimony whereof we affix our signatures in presence of two witnesses.

ALBERT P. M. KLOSTERMANN.
HUGO O. R. LUBKE.
